US0D1039262S

(12) **United States Design Patent** (10) **Patent No.:** **US D1,039,262 S**
(45) **Date of Patent:** **** Aug. 20, 2024**

(54) **SUN SHADE**

(71) Applicant: **GUANGDONG DERUI SMART HOME CO., LTD.**, Foshan (CN)

(72) Inventor: **Yanjuan Wei**, Foshan (CN)

(73) Assignee: **GUANGDONG DERUI SMART HOME CO., LTD.**, Foshan (CN)

(**) Term: **15 Years**

(21) Appl. No.: **29/885,074**

(22) Filed: **Feb. 20, 2023**

(51) LOC (14) Cl. **03-03**

(52) U.S. Cl.

USPC **D3/5**

(57) **CLAIM**

The ornamental design for a sun shade, as shown and described.

DESCRIPTION

FIG. 1 is a perspective view of a sun shade showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2;

FIG. 11 is an enlarged view of portion 11 shown in FIG. 2;

FIG. 12 is an enlarged view of portion 12 shown in FIG. 2; and,

FIG. 13 is an enlarged view of portion 13 shown in FIG. 2.

The dash-dash broken lines in the drawings depict portions of the sun shade that form no part of the claimed design. The dot-dash broken lines represent boundaries of the enlarged portions and form no part of the claimed design.

1 Claim, 13 Drawing Sheets
